(57) **CLAIM**

The ornamental design for a roof cross bar for vehicle, as shown and described.

DESCRIPTION

FIG. 1 is a front perspective view of a roof cross bar for a vehicle according to the present invention.

FIG. 2 is a front view of the roof cross bar shown in FIG. 1. FIG. 3 is a rear view of the roof cross bar shown in FIG. 1. FIG. 4 is a left-side view of the roof cross bar shown in FIG. 1.

FIG. 5 is a right-side view of the roof cross bar shown in FIG. 1.

FIG. 6 is a top plan view of the roof cross bar shown in FIG. 1.

FIG. 7 is a bottom view of the roof cross bar shown in FIG. 1; and,

FIG. 8 is another perspective view of the roof cross bar according to the present invention.

1 Claim, 5 Drawing Sheets
